EYEGLASS FRAME OR THE LIKE

Edward W. Smith and Alexander C. Kono, Woodside, N.Y., assignors to Kono Manufacturing Co. Inc., Woodside, N.Y., a corporation of New York

Filed Dec. 5, 1963, Ser. No. 77,676

Term of patent 14 years

(Cl. D57—1)

FIG. 1 is a front view of an eyeglass frame or the like, showing our new design;

FIG. 2 is top view thereof; and

FIG. 3 is a side elevational view thereof.

Our design for the eyeglass frame disclosed is characterized by the particular elements superimposed over the upper front of the outer ends, following the curved concave curve of said outer ends and curving backward to join with the temple elements as shown.

We claim:

The ornamental design for an eyeglass frame or the like, substantially as shown and described.
